Specification for Design.

Patented Nov. 27, 1917.

Application filed September 13, 1917. Serial No. 191,293. Term of patent 14 years.

To all whom it may concern:

Be it known that I, MACK BRALEY, a citizen of the United States, residing at Akron, in the county of Summit and State of Ohio, have invented a new, original, and ornamental Design for Vehicle-Wheel Tires, of which the following is a specification, reference being had to the accompanying drawings, forming part thereof.

In the drawings Figure 1 is a view in side elevation of a portion of a vehicle tire, showing my new design, and

Fig. 2 is a sectional view of the same.

I claim:

The ornamental design for a vehicle wheel tire, substantially as shown.

MACK BRALEY.
